UNITED STATES PATENT OFFICE.

AXEL H. STAF, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A PUFF-BOX OR SIMILAR ARTICLE.

54,358.

Specification for Design.

Patented Dec. 30, 1919.

Application filed May 23, 1919. Serial No. 299,353. Term of patent 14 years.

To all whom it may concern:

Be it known that I, AXEL H. STAF, a citizen of the United States, residing at Providence, in the county of Providence and State of Rhode Island, have invented a new, original, and ornamental Design for Puff-Boxes or Similar Articles, of which the following is a specification, reference being had to the accompanying drawing, forming part thereof.

The figure in the drawing is an obverse view of a puff box, the section indicated, showing my design.

I claim—

The ornamental design for a puff box or similar article, as shown.

AXEL H. STAF.

Witnesses:

JOHN H. RING,
W. F. KINGMAN.
